FOOD COOKING, WARMING, AND SERVING TABLE

Otto E. Werner, Skokie, Ill., assignor to Automatic Canteen Company of America, Chicago, Ill., a corporation of Delaware

Filed Sept. 25, 1961, Ser. No. 66,847

Term of patent 14 years

(Cl. D81—10)

FIG. 1

FIG. 2

FIG. 3.

FIGURE 1 is a perspective view of a food cooking, warming and serving table, embodying my new design;

FIGURE 2 is a perspective view showing the opposite sides of FIGURE 1, and

FIGURE 3 is a fragmentary elevational view taken from the lower left of FIGURE 1.

I claim:

The ornamental design for food cooking, warming, and serving table, as shown.
